[57] CLAIM

The ornamental design for a handle for a kitchen utensil, as shown and described.

DESCRIPTION

FIG. 1 is a top, left side perspective view of a handle for a kitchen utensil showing my new design; the broken line showing of the spool bowl is illustrative of environmental structure only and forms no part of the claimed design;

FIG. 2 is a front elevational view thereof on an enlarged scale;

FIG. 3 is a top plan view thereof on an enlarged scale; FIG. 4 is a left side elevational view, the opposite side being a mirror image thereof;

FIG. 5 is a bottom plan view thereof;

FIG. 6 is a rear elevational view thereof on an enlarged scale; and

FIG. 7 is a top, left side perspective view of a modification of my new design for a handle for a kitchen utensil; the broken line showing of the spoon bowl is illustrative of environmental structure only and forms no part of the claimed design. The modified design is essentially identical in all respects to FIGS. 1-6 except for the tang end thereof.

The design is characterized by the specific configuration of the elongated hand grip portion in association with the inset neck portion as best described in FIGS. 1 and 4.
